US0D1086133S

(12) **United States Design Patent** (10) Patent No.: **US D1,086,133 S**
(45) Date of Patent: ** Jul. 29, 2025

(54) **CONTROLLER**

(71) Applicant: **Meta Platforms Technologies, LLC**,
Menlo Park, CA (US)

(72) Inventors: **Peter Wesley Bristol**, Seattle, WA
(US); **Yi-yaun Chen**, Seattle, WA (US);
Mauricio Romano, Redmond, WA
(US); **Peter Allan Chase Newbury**,
Nice (FR)

(73) Assignee: **Meta Platforms Technologies, LLC**,
Menlo Park, CA (US)

(**) Term: **15 Years**

(21) Appl. No.: **29/910,042**

(22) Filed: **Aug. 14, 2023**

CLAIM

The ornamental design for a controller, as shown and described.

DESCRIPTION

FIG. 1 is a front perspective view of a controller showing the claimed design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the figures illustrate portions of the controller that form no part of the claimed design.
